Primary Examiner — Catherine Tuttle(57) **CLAIM**

The ornamental design for a sports ball catcher, as shown and described.

DESCRIPTION

FIG. 1 is a perspective front view of a sports ball catcher; FIG. 2 is a front elevation view of the sports ball catcher; FIG. 3 is a rear elevation view of the sports ball catcher; FIG. 4 is a left side elevation view of the sports ball catcher; the right side view being a mirror image thereof; FIG. 5 is a top plan view of the sports ball catcher; and, FIG. 6 is a bottom plan view of the sports ball catcher. The numerals shown in broken lines in FIGS. 1 and 2 are for illustrative purposes only; and form no part of the claimed design.
